UNITED STATES PATENT OFFICE.

JAMES T. DAHL, OF SEATTLE, WASHINGTON.

SAFETY DEVICE FOR SUBMARINES.

1,233,892.

Specification of Letters Patent. Patented Sept. 4, 1917.

Application filed April 20, 1915. Serial No. 22,619.

To all whom it may concern:
Be it known that I, JAMES T. DAHL, a citizen of the United States, residing at Seattle, in the county of King, State of Washington, have invented certain new and useful Improvements in Safety Devices for Submarines; and I do hereby declare the following to be a full, clear, and exact description of the invention, such as will enable others skilled in the art to which it appertains to make and use the same.

This invention relates to safety devices for submarines.

The object of the invention resides in the provision of a safety device for submarines through the instrumentality of which a fresh supply of air may be secured by the crew in the event of an accident and the resultant failure of the submarine to rise to the surface of the water, said device also enabling the crew to obtain the necessary air for expelling the water from the ballast tanks to cause the submarine to rise, the device thus having the dual purpose of saving the lives of the crew and recovering the submarine.

A further object of the invention resides in the provision of a device of the character named, which will be simple in construction, comparatively inexpensive to manufacture, reliable and efficient in use, and easily operated.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a view showing the device associated with a submerged submarine and the parts thereof in the position they would occupy in supplying air from above the surface of the water to the submarine;

Fig. 2, a diagrammatic view of the device;

Fig. 3 a vertical section of the buoy pocket with the buoy shown therein in elevation;

Fig. 4, a section on the line 4—4 of Fig. 3;

Fig. 5, a section on the line 5—5 of Fig. 4;

Fig. 6, a vertical section through the up-

per portion of the air buoy with the main valve in closed position;

Fig. 7, a view at right angles to Fig. 6 with the main valve in open position;

Fig. 8, a sectional view showing the connection between the buoy and the foul air and fresh air pipes;

Fig. 9, a section on the line 9—9 of Fig. 6;

Fig. 10, a section on the line 10—10 of Fig. 6, and

Fig. 11, a section on the line 11—11 of Fig. 3 showing the locking mechanism of the door of the buoy pocket.

Referring to the drawings A indicates generally a submarine and B the safety device associated therewith and carried therein as clearly shown in Fig. 1.

This safety device comprises a buoy pocket 15 suitably mounted within the submarine and including a hinged top 16 forming part 75 of the hull of the submarine and adapted to be locked and released through the medium of a toggle locking device 17, said locking device being operated through the medium of push rods 18 slidably mounted in the top 16 as clearly shown in Fig. 11. Rotatably mounted within the pocket 15 is a shaft 19 including hollow terminal sections 20 and 21 and a solid intermediate section 22. Surrounding the shaft 19 within the pocket 15 85 in spaced relation to said shaft and held fixed with respect to the latter by means of braces 23 is a drum 24 provided with end flanges 25. Secured to the inner end of the hollow section 20 of the shaft 19 is one end 90 of a fresh air pipe 25', while a foul air pipe 26 has one end thereof in communication with the inner end of the hollow section 21. The fresh air pipe 25 and the foul air pipe 26 merge into a single pipe 27 provided with 95 a longitudinal partition 28 forming the fresh air passage 29 and the foul air passage 30. This pipe 27 is flexible and is adapted to be wound upon and unwound from the drum 24 in a manner that will hereinafter 100 appear. Mounted upon the wall of the pocket 15 and surrounding the outer end of the hollow section 20 is a cap 31 which communicates with the interior of said sections through an opening 32 formed in the shaft 105 19. Also mounted upon the wall of the pocket 15 is a cap 33 the interior of which communicates directly with the interior of the section 21. Fixed on the shaft 19 adjacent the cap 31 is a gear 34 which meshes 110

with a gear 33 rotatably mounted on a shaft 36 carried by a bracket 37, said gear 35 having fixed thereto a crank 38 whereby the gear 35 may be readily rotated for the purpose of rotating the drum 24 to wind the pipe 27 thereon.

The air buoy of the device comprises a hollow conical member 39 the minor end of which is secured to the end of the pipe 27 by means of a suitable coupling 40 one section of which includes a tubular member 41 having spaced longitudinal partitions 42 forming a foul air passage 43 and a fresh air passage 44 and between which partitions the partition 28 is confined. The other section of the coupling 40 also includes spaced partitions 45 forming a foul air passage 46 and a fresh air passage 47 which in the assembled coupling communicate respectively with the passages 43 and 44. The pipe 27 is secured around the member 41 and clamped thereon through the medium of a suitable clamping band 48. Secured within the passages 46 and 47 are the ends of a foul air pipe 49 and a fresh air pipe 50. These pipes 49 and 50 extend through the top of the buoy 39 and through a tubular member 51 secured upon the top of the buoy 39. Threaded in the upper end of the tubular member 51 is a cap 52 through which the upper ends of the pipes 49 and 50 are engaged, said cap serving to hold the upper ends of said pipes as will be obvious. The outer side of the cap 52 is dished to form a seat for a valve 53. Depending from this valve 53 are arms 54 which are slidably engaged through the cap 52. Pivoted on suitable brackets 55 carried by the pipe 50 are levers 56 corresponding ends of which are pivotally connected to the lower ends of the arms 54. The other corresponding ends of the levers 56 are slotted longitudinally and have engaged through said slots a stud 57 projecting from a stem 58 which latter carries spaced pistons 59 and 60, said pistons working in the pipe 50 as will be obvious. The stud projects through a suitable opening 61 in the pipe 50 and this opening is enlarged as at 62 for a purpose that will presently appear. By this construction it will be apparent that when the pistons 59 and 60 are forced upwardly the valve 53 will be pressed firmly to its seat while downward movement of the pistons 59 and 60 will raise the valve 53 from its seat. Mounted on the pipe 50 beneath the piston 60 is an inwardly opening check valve 63 through the instrumentality of which communication between the interior of the pipe 50 and the interior of the member 51 is afforded under certain conditions. Mounted on the member 51 and covering the upper end thereof is a bell 64 which is held in proper relation to the member 51 by a perforated plate 65 secured to both the member 51 and the bell 64. Mount-

ed on the outer side of the valve 53 is a bracket 66 on which is pivoted a lever 67. One end of this lever is adapted to engage a contact 68 carried by the valve 53 while the other end thereof has pivotally connected thereto one end of a rod 69 slidably engaged in the plate 65 and carrying on its lower end a float 70 disposed normally at its lower end outward of the lower end of the bell 64, in which normal status the lever 67 is out of engagement with the contact 68. The lever 67 and contact 68 have connected thereto the conducting wires 71 of a signal circuit which when closed is adapted to sound a suitable signal within the submarine. These wires 71 are mounted between the partitions 45, partitions 43, in the partition 28 and are then directed through the pipe 25, through the section 20 of the shaft 19 and are connected respectively to ring terminals 72 fixed on the shaft 19 and engaging contacts 73 supported by the cap 31. The circuit is completed by wires leading from the contacts 73. The circuit is also utilized as a telephone circuit by extending same through the top of the bell 64 by means of wires 74.

The device further comprises a tank 75 the interior of which is connected with the interior of the pocket 15 at a point near the top of the latter by means of a pipe 76 provided with a valve 77. The tank 75 is also connected with the interior of the cap 33 by a pipe 78 provided with a valve 79. A pipe 80 leading from one end of the tank 75 is connected to a pump 81 and the pump is also connected to the interior of the cap 31 by means of a pipe 82. The pipe 80 is provided with a valve 83, while a branch pipe 84 connects the pipes 80 and 82 and is provided with a valve 85 and has mounted thereon a pressure gage 86. Leading from the pipe 80 is a branch pipe 87 including a valve 88. A pipe 89 communicating with the pocket 15 at the bottom thereof is adapted to connect at its opposite end (not shown) with the sea, while the branch pipe 87 communicates with the interior of the submarine.

In the operation of the device, assuming that the submarine is submerged and it is desired to obtain fresh air from the surface of the sea, the valve 77 is opened to permit water to enter the pocket 15 by way of pipe 89 and fill the pocket. As the pocket fills with water the latter will come into engagement with the float 70 and cause same to rise with the result that the lever 67 is rocked into engagement with the contact 68 and the signal in the submarine sounded. The valve 77 is then closed to prevent water flowing from the pocket 15 into the tank 75 by way of the pipe 76. When the buoy 39 is to be released the valve 85 is opened and the valve 83 slightly opened to raise the pressure in the pipe 82 and pipe 84 to 20 or 30 pounds. This compressed air will then

flow through the various fresh air pipes and strike the piston 60 causing the latter to move upwardly and firmly seat the valve 53. The pressure of the water outside the submarine and in the pocket 15 is now the same and the locking device 17 is operated to release the top 16 by pressing the rod 18. As soon as the top 16 is released the buoy 39 will rise to the position shown in Fig. 1 and dispose the bell 64 entirely above the surface of the water. When the buoy is positioned as shown in Fig. 1 no water will be in contact with the float 70 and as a result the signaling circuit will be broken and the sounding of the signal in the submarine stopped to indicate that the buoy is in proper position to begin to take in air. Valve 85 is then closed and valve 73' is opened so that air from the tank will flow through the foul air pipe and pass into the upper end of the fresh air pipe 50 and against the piston 59. As a result the pistons 59 and 60 will be forced downwardly and the enlarged portion 62 of the opening 61 will be placed in communication with the extreme upper end 25 of the pipe 50. This downward movement of the pistons 59 and 60 will cause the valve 53 to be unseated and thus places the upper ends of the pipes 49 and 50 in communication with the atmosphere. At the same time valve 73' and valve 83 are opened and the pump is set in operation. Valve 73' is then closed and the operation of the pump continued. Valve 88 is then opened slightly 30 as is likewise valve 79 which latter is an entrance valve from the side and is regulated so the pressure is suitable. The air thus circulated by the pump can be utilized for the necessary purposes, such as removing 35 the water from the ballast tanks and supplying air thereto causing the submarine to rise.

When the piston 60 is raised as stated in the previous description of the operation the valve 63 prevents the passage of air to the exterior of the tube 50 and maintains the desired pressure against the piston 60. When pumping fresh air down the tube 50 in the manner previously described it will be obvious that the valve 63 permits the air to enter the tube 50 from the exterior thereof.

What is claimed is:—

1. A safety device for submarines com-

prising a pocket adapted to be mounted within the submarine and including a releasable hinged top forming part of the hull, a reel rotatably mounted within the pocket, a buoy loosely disposed in the pocket, a tubular member on the top of the buoy, a bell engaged over the upper end of the tubular member, foul air and fresh air pipes extending through the buoy and the tubular member and having corresponding ends opening through the outer end of the tubular member, a valve for closing and opening said corresponding ends of the pipe, pneumatically operated means for holding said valve closed during the rise of the buoy to the surface of the water and for opening said valve when the buoy is disposed upon the surface of the water, said pipes being connected to the reel, and means for drawing air in the fresh air pipe and for forcing air out of the foul air pipe when the buoy is floating on the surface of the water. 75

2. A safety device for submarines comprising a pocket adapted to be mounted within the submarine and including a releasable hinged top forming part of the hull, a reel rotatably mounted within the pocket and including a spindle having independent passages opening at corresponding ends of the exterior of the pocket, a buoy loosely disposed within the pocket and adapted to rise to the surface of the water when the top of the pocket is released, means for filling said pocket with water prior to the release of the top, fresh air and foul air pipes connected to the buoy and adapted to have corresponding ends disposed above the surface of the water when the buoy is released from the pocket said pipes being connected at their other corresponding ends to the spindle of the reel in communication with respective passages in said spindle and adapted to be wound upon and unwound from the reel and means for drawing air in the fresh air pipe and forcing air out of the foul air pipe when the buoy is floating on the surface of the water. 100 105

In testimony whereof, I affix my signature, in the presence of two witnesses.

JAMES T. DAHL.
